METHOD AND MEANS FOR IMPROVING
RADIORECEPTION

Maurice H. Livingston, Chicago, Ill.

Application April 27, 1931, Serial No. 533,221

15 Claims. (Cl. 250—20)

This invention relates to improvements in radio reception and has special reference to means and methods of reducing or eliminating interference and static discharges, and rendering the 5 radio receiving apparatus more sensitive to slight differences in wave length, thus making it possible to separate sending stations which are close together and generally to means and methods for improving reception in all desired qualities.

10 A further object of the invention is to provide means for radio or wireless reception in the use of which all inside or outside aerials and lightning arrestors, etc., shall be eliminated, in fact, in which all connections with separate or fixed 15 devices of this character shall be eliminated, it being only necessary to make connection with a current supply circuit such as an electric lighting circuit.

20 A further object is to provide such a means 20 of radio or wireless reception as shall permit the placing of a radio receiving set in any desired or convenient room or place without the necessity of installing or making connection with aerials, lightning arrestors or the like, it being merely 25 necessary to plug the receiving wire of the set into any convenient connection such as a wall socket or lamp socket of the local or house lighting system.

25 In other words, by the use of this improvement in reception, the portability of receiving sets is greatly enhanced.

The invention resides in a novel method of subjecting a novel form of antenna to the inductive influence of a double connection with an associated source of current, adapted to be closed for 35 setting up or starting inductive influence and capable of operating in open circuit condition.

A simple form of novel apparatus by which the method can be carried out includes a double circuit wire adapted to be plugged in to an electric light circuit, and provided at its free end with a current using device such as a lamp and a switch for turning the lamp on and off, and a single, flexible antenna wire adapted to have one of its 40 ends secured to the antenna post of a receiving set and to be interwoven with the double circuit wire for a portion only of its length, the free end of the antenna wire being spread out in peculiar forms, the functions of which are to filter and clarify the induced impulses and quietly discharge 45 all unwanted vibrations or waves.

The spread out end portion of the antenna wire is bare of insulation and, preferably, certain parts thereof are covered with tinfoil. This free 50 end portion of the antenna wire includes rela-

tively short twisted sections connected by a section in which the individual wires of the flexible antenna are spread out in a plane, preferably in a disk-like shape of appreciable diameter, and the free ends of the several individual wires are spread out in a fan shape, preferably in the plane with the disk-like formation.

The interweaving of the antenna wire with the double circuit wire preferably begins at the 5 base of the spread out free end of the antenna wire and extends approximately about two feet to the free end of the double circuit or, in other words, to the lamp socket.

A peculiar and advantageous feature of the 10 invention resides in the fact that sudden impulses of current or damped wave trains, such as are set up by approximately near by electricity using devices such as electric carpet sweepers, ray or other high voltage machines, 15 defective connections on street railway lines, etc., cannot pass through to the radio set but are stopped or eliminated by the device. There may be a slight click when a near-by electric light 20 is turned on but none when it is turned off.

The invention will be more readily understood 25 by reference to the accompanying drawing forming part of this specification and in which

Fig. 1 is a fragmentary, elevational view of a 30 novel apparatus which I have devised for carrying out my invention; and

Fig. 2 is an enlarged, fragmentary view of a portion of Fig. 1.

In said drawing, 1 represents a double circuit wire provided at one end with means such as the 35 usual two prong plug 2 for connecting this circuit wire with a current supply circuit such as the house lighting system. At its free end, this double circuit wire 1 is provided with a current using device, preferably in the form of a small electric lamp 3 and a switch means such as the 40 pull lamp socket 4 for connecting and disconnecting the lamp 3.

Preferably, a portion of this double circuit, as 45 shown at 5, is lead through a suitable case or box 6. The case 6 may be made of any suitable non-metallic material such as wood, cardboard, fiber, or the like. The case is merely for the purpose of protecting the parts mounted therein against inadvertent damage or disturbance.

The double circuit wire 1, when connected to the house lighting circuit or any similar electric system, brings to the apparatus the high tension impulses picked up by the supply circuit, the supply system serving as an aerial for the col- 50

lection and transmission of the projected radio waves.

The function of the device 3 which can be connected to use at will, is to assist the set to 5 receive.

For taking off these waves which are brought in by the double circuit wire 1 and making use of them in a radio receiving set, I provide a radio antenna wire 7 which is preferably a flexible 10 wire made up of a number of small wires 8. This antenna wire 7 is interwoven for a portion of its length with the double circuit wire 1, as shown at 9. The interwoven part 9 is, preferably, approximately two feet long terminating adjacent 15 to the lamp socket 4 at one end and at substantially the center of the bottom of the box 6 at the other end. One end 10 of the antenna wire 7 is connected to the antenna lead in post 11 of a radio receiving set (not shown) and the 20 other end terminates within the box 6. Preferably, the antenna wire 7 is bound rigidly to the wire 1, at the point within the box where it diverges, by insulation material 12 and the two are fixed to the bottom of the box as by staples 25 13 for the purpose of receiving the terminal part 14 of the antenna wire in upright position and free of the walls of the box 6.

The terminal part 14 of the antenna wire is 30 bared of insulation covering, beginning approximately at the point where the insulation 12 terminates, and this terminal part is formed to provide an efficient means for eliminating static charges which would otherwise pass into the receiving apparatus and produce undesired sounds. 35 This terminal part of the antenna is also peculiarly formed to assist in reducing or eliminating interference.

Beginning at the point 15 at the termination of 40 the insulation, the antenna wire is twisted tightly in one direction, as shown at 16, for a short distance, preferably about an inch in length, then the separate wires 8 of the antenna wire are spread out into the form of a flat loop 17 of, preferably, approximately two inches in diameter and 45 with the individual wires spaced from each other. Beyond the loop 17 the wires 8 of the antenna wire 7 are again twisted tightly together for a short distance, as shown at 18, this section also being approximately one inch long and, preferably, 50 the wires are twisted in the opposite direction to the twisting at 16.

Beyond the section 18, the individual wires 8 of the antenna wire 7 are spread out radially in fan shape, as shown at 19, the free spread out 55 ends of the wires 8 being, preferably, about four to six inches long.

The fan shape 19 is preferably flat and is preferably in substantially the same plane as the flat loop 17.

60 The portion of the antenna wire 7 which is interwoven with the double circuit wire, as shown at 9, is in peculiar inductive relation to the double circuit wire. In its passage through this section, it passes from one side to the other of both of the 65 wires of the double circuit wire in close and tight proximity thereto and the result amplified by the receiving apparatus is what may be termed perfect radio reception.

70 The filtering and clarifier loop 17 and the dispenser 19 serve to eliminate all waves which are but slightly different from the waves for which the receiving apparatus is set, with the result that the possible tuning out of any but the one station wanted has been brought to a very fine 75 point. Indeed, stations which are supposed to

operate on the same wave length but which actually vary a trifle have been separated.

As a further refinement, I cover certain parts of the terminal with a layer of tinfoil such, for instance, as the insulation 12 and the lower portion of the lower twisted section 16, as shown at 20; also the outer wires of the clarifier loop 17, as shown at 22. This addition of the tinfoil covering serves as a slight or small condenser to assist in filtering and clarifying reception.

The single flexible antenna wire 7 is, preferably, approximately six to eight feet long from end to end, and the double circuit wire 1 is, preferably, approximately nine feet long from the plug 2 to the lamp socket 4.

The device is arranged to be hung upon a wall, being provided with a suspension device such as an eye 23 fixed at its upper end but it is equally efficient in any other position.

Applicant believes that the method of collecting 20 radio waves and reducing or eliminating interference which is disclosed herein, consists in subjecting a portion of a single flexible antenna wire to the inductive effect of a double circuit aerial wire, transmitting the desired waves to the receiving set by the connection of one end of the antenna wire with the set, and reducing or eliminating undesired electrical impulses that is interference, by the use of the loops 7 and spreading out ends 10 of the antenna wire.

As many modifications of the invention will readily suggest themselves to one skilled in the art, I do not limit or confine the invention to the specific mode or method or to the specific details of construction herein described and illustrated.

I claim:

1. In an apparatus of the kind and for the purpose described, a flexible radio antenna wire having a free end and being closely interwoven with a pair of electric circuit wires for a relatively short part of the total length thereof, the free end of the antenna wire having the individual wires thereof spread out in approximately fan shape and located at a point removed from the end of the electric circuit wires.

2. In an apparatus of the kind and for the purpose specified, a flexible double circuit wire adapted to be connected at one end to a current supply circuit such as an electric light circuit, a current using device such as a lamp at the free end of said double circuit wire, means for connecting and disconnecting the current using device, an antenna wire adapted to be connected at one end of the antenna post of a radio receiving set, and at a distance from said end closely interwoven with the double circuit wire beginning adjacent to the current using device and continuing but a relatively short distance, the free end of the antenna wire being spread out into fan shape and provided with a plurality of terminal points.

3. The invention as defined in claim 1, the free end of the antenna wire being bared of insulation and a portion thereof spread out in the form of a flat loop or ring between the point where it leaves the double circuit wire and the spreading out of the free end.

4. The invention as defined in claim 1, the free end of the antenna wire being bare, and the individual wires thereof being twisted tightly together for a short space as it leaves the double circuit wire, then spread out into a flat ring-like loop, then twisted together tightly again for a short distance and then spread out fan-wise providing a plurality of thin, relatively long points.

5. The invention as defined in claim 1, the double circuit wire being in the form of two insulated wires twisted together and the antenna wire being interwoven therewith.

5 6. The invention as defined in claim 1, the free end of the antenna wire being bared and parts thereof covered with tinfoil.

7. In an apparatus of the kind and for the purpose specified, a flexible double circuit wire adapted to be connected at one end to a current supply circuit such as an electric light circuit, a current using device such as a lamp at the free end of said double circuit wire, means for connecting and disconnecting the current using device, an antenna wire adapted to be connected at one end to the antenna post of a radio receiving set, and at a distance from said end interwoven with the double circuit wire beginning adjacent to the current using device and continuing but a relatively short distance, the free end of the antenna wire being bared, and the individual wires thereof twisted tightly together for a relatively short distance, then spread out in a flat loop form, then again twisted tightly together for a like relatively short distance, then spread out in a fan shape, the first twisted portion being partly covered with tinfoil and the outer strands in the flat loop being likewise covered with tinfoil.

8. The invention as defined in claim 1, the free end of the antenna wire extending out from the double circuit wire at substantially right angles thereto.

9. The invention as defined in claim 1, the free end of the antenna wire extending out from the double circuit wire at substantially right angles thereto, and insulation material binding the antenna wire to the double circuit wire at the point of divergence, and means for retaining same rigidly in place.

40 10. The invention as defined in claim 1, the free end of the antenna wire extending out from the double circuit wire at substantially right angles thereto, and insulation material binding the antenna wire to the double circuit wire at the point of divergence, and means for retaining same rigidly in place, and said insulation material being covered with tinfoil which also extends for a short distance on the free end of the antenna wire.

45 11. In apparatus of the kind and for the pur-

pose specified, a multiple stranded antenna wire, a double wire adapted at one end to be connected to a current supply circuit such as an electric light circuit, a device such as an electric lamp for using current at the opposite end of said double wire, the two wires of same being twisted together, and the antenna wire interwoven tightly with the double wire for a portion only of its length adjacent to the electricity using device, the single wire covered with insulation where it is interwoven with the double wire, the single wire being bared of insulation beyond the termination of the interwoven section and said single wire terminating near said end of the interwoven section and the ends of the several strands thereof spread out in fan shape in approximately a single plane.

12. The invention as defined in claim 11, and the strands of a portion of the bared end of the single wire being spread out in the form of an open disk or loop.

13. The invention as defined in claim 11, the bared end of the single wire being twisted in one direction adjacent to its point of departure from the double wire, then spread out to form a disk or loop, then twisted for a short distance in the opposite direction, then the ends of the strands spread out in fan shape in approximately a single plane.

14. The invention as defined in claim 11, the double circuit wire being approximately nine feet long from end to end, the antenna wire being approximately seven feet long and interwoven with the double circuit wire approximately two feet.

30 35 15. The invention as defined in claim 11, the bared end of the single wire being twisted in one direction adjacent to its point of departure from the double wire, then spread out to form a disk, then twisted for a short distance in the opposite direction, then the ends of the strands spread out in fan shape in approximately a single plane, the disk being approximately two inches in diameter, the twisted sections of the antenna wire being each approximately one inch in length, and the spread out ends of the strands being approximately five inches in length.

MAURICE H. LIVINGSTON.
